CHECK VALVE FOR DOOR CLOSERS

John F. Voelkel, Brooklyn, N. Y., assignor, by
mesne assignments, to Marie Anna Bommer
Frohlich

Application May 13, 1940, Serial No. 334,779

1 Claim. (Cl. 251—127)

This invention relates to a check valve for door closers and checks, and has for its object to provide an improvement therein whereby the parts operate with greater facility, are more simple and at the same time the control is improved.

In door closers and checks of this kind, which operate with oil as a fluid medium, there has been considerable difficulty in adjusting the passages for the oil so as to determine the amount of oil to pass through. A further difficulty has been that after door closers and checks of this kind are installed in the floor of a building, it is very difficult to obtain access thereto for either adjustment or repair.

The purpose of this invention is to overcome these objections and the invention of the improvement herein described consists in providing regulative means after the door closer and check have been installed without the necessity of taking the closer and check away from its installed position or without the necessity of removing the coverings either of wood or cement.

For this purpose my invention consists of the improvement hereinafter described, the embodiment of which is shown in the drawing and which will be finally pointed out in the claim.

In the accompanying drawing:

Figure 1 is an end view of my improved door closer and check.

Figure 2 is a vertical longitudinal section taken on line 2—2 of Figure 1.

Figure 3 is a detailed section taken on the line 3—3 of Figure 1, and

Figure 4 is a detailed section taken on line 4—4 of Figure 2.

Similar characters of reference indicate corresponding parts throughout the various views.

Referring to the drawing, and more particularly to Figures 1 and 2, the usual housing is shown in dotted lines in Figure 1 and indicated by the character 10. This housing has inwardly projecting shoulders 11 and upon these shoulders the projecting shoulders 12 of the casing 13 are placed. The shoulders 12 are provided with screw threaded socket portions 14 adapted to receive screw threaded members therein.

Within the casing 13 a piston 15 is arranged, which has a piston pin 16 engaging the piston rod 17.

The interior of the casing 13 forms a cylindrical member 18, for the movement of the piston 15 and beyond this cylindrical member 18, an enlarged cut-out portion 19 is provided which has a larger diameter than the diameter of the cylindrical portion 18.

The piston 15 is also provided with a conduit 20 inclined in position as it passes through the piston 15 and having an enlarged portion 21 in which there is placed a ball 22, held therein by the pin 23.

The piston head 13a has a longitudinal conduit 24 and another conduit at right angles thereto indicated by 25.

The parts just described are old and well known.

The improvement in a structure of the kind described consists in providing the exterior of the casing 13 with a vertically slidable cylindrical member 30, which member has a bore 31 extending transversely therethrough. The internal configuration of this bore is of general oval or elliptical shape as is shown in Figure 4. The actual shape is not important, but what is important is that the bore should be larger than the diameter of the pin 33 supported in the walls of the casing 13 and passing through the bore 31.

The lower part of this member 30 is shaped in the form of a cone and indicated by 34 so as to rest upon similarly inclined sides 35 in the casing 13.

The conically shaped member 34, when resting upon the similarly inclined seats 35, acts to throttle the conduit 25 and control the passage of oil or other fluid therethrough.

The external circumference of the cylindrical member 30 is somewhat smaller than the circumference of the bore 36 in the casing 13 so that there is a freedom of movement, both vertically and transversely of the cylinder member 30 within the bore 36 of the casing 13, the conically shaped end 34 finding its own position in respect to the sides 35.

The upper part of the cylindrical member 30 is provided with a spherically shaped concave cavity 37, which is engaged by a similarly shaped end, but of convex form indicated by 38 of a rod or spindle 39. This rod 39 has at its other end a screw threaded portion 40 which engages corresponding screw threads 41 of the floor board 42 shown in Figure 2.

The operation of the improved device is as follows:

After the door closer and check have been placed in position by the carpenter or other workman and adjusted as thought to be proper for the operation of that particular door, the cylindrical member 30 is adjusted by being placed in position with its conical end 34 easily resting upon the inclined portion 35. The pin 33 is then inserted into suitable openings of the casing 13, and caused to

pass in engaging these registered openings, through the irregularly shaped opening 31 of the cylinder member 30.

There is a certain amount of looseness of movement of the member 30 in respect to the casing 13 due to the fact that the bore 31 is larger than the pin 33. Were the diameter of the pin 33 of exactly the same size as the bore 31, there would not be this freedom of movement. The invention, however, consists in providing this freedom of movement as described.

Due to the fact that the upper part of the cylinder 30 is provided with the concave portion 37 and the pin 39 is provided with the convex portion 38, the positioning of the cylindrical member 30 is controlled to a certain extent by the spindle 39 in that at whatever position the convex portion 38 may contact with the concave portion 37, a self-aligning of the member 30 with the spindle 39 will take place.

This is important because after the door closer and check has been installed, its adjustment can be carried out without breaking up the floor under which it has been installed. The regulation of the spindle 39 passing through the floor 42 and being adjustable in respect thereto, permits adjustment of the cylinder member 30 from the outside of the upper part of the floor.

The upper end of the member 39 is provided with a slot 40a for the entrance of a tool so as to rotate the member 39 for adjustment purposes described.

In Figure 3 is shown a check valve which is arranged in the piston 15 in the position shown in Figure 1. This check valve consists of an opening 45 in a seat 46, a cylindrical portion 47 and a screw threaded portion 48.

Within the cylindrical portion 47 is a ball 49 of an exterior diameter almost equal to the interior diameter of the cylindrical wall 47 and the ball is adapted to rest upon a conically inclined shoulder 46 and thereby when so resting thereon, closing the passage 45.

The screw threaded portion 48 of the piston 15 is engaged by a member 50 having an external screw thread 51 engaging the internal screw threads 48 and this member 50 may be provided with a transverse slot to enable the member 50 to be engaged by a screw driver or other tool. This member 50 also has a bore 52 and a conical seat 53 for one end of the spring 55.

Interposed between the conical seat 53 of the member 50 and the ball 49 is a spiral spring 55, which serves to press the ball 49 against the conical seat 46. By moving the member 50 inwardly, a greater pressure is exerted upon the spring 55 and by moving the member outwardly, a less pressure upon the spring 55 results. This regulation of seating power of the spring 55, which spring presses the ball 49 against its seat 46, is then determined by member 50. Thus the fluid which passes from the interior of cylinder 13 through the piston 15, from one side to the other of the piston 15, is regulated not alone by the valve 22 in the manner well known, but a more refined and a more accurate regulation results from the use of the regulating device shown in Figure 3.

My device is, therefore, very simple in its construction, may be easily manufactured and may be equally easily installed.

In one embodiment of the invention the center lines or axes of the valve member 30 and the adjusting member 39 are in substantial alignment and disposed substantially vertically and with the cone seat 34 concentric of the longitudinal center or axis of the valve member 30. There is no connection between the members 30 and 39, that is no direct mechanical connection. The longitudinal center or axis of the adjusting member 39 is fixed by the support 42 while the center line or axis of the member 30 may move laterally or horizontally within the limits of the pin member 33 in all radial directions to permit the cone 34 to accommodate itself by its weight into a central or proper sealing position upon the casing seat 35 which may be concentrically arranged in the casing fluid passage 25.

The ball and socket joint or confronting faces 37, 38 enable this horizontal movement of the valve member 30 with respect to the fixed axis of the adjusting member 39. The surfaces 37, 38 being parts of spheres are self centering causing the floating valve member 30 to seek a central position with respect to the adjusting member 34 whenever the valve member 30 moves up in response to the pressure of the fluid or is forced down upon its seat by the pressure of the adjusting member 39 from above.

Having described the invention in character with an embodiment thereof, it is not intended that the invention be limited to the precise form and arrangement, but that the scope of the invention is set forth in the appended claim.

What is claimed is:

A check valve for use in a door closer and check, comprising a valve chamber having a conical valve seat, a valve member in said chamber having a concaved upper end and a lower end conically shaped and adapted to cooperate with said conical valve seat, said valve chamber above said seat being diametrically larger than said valve member to permit relative movement of the latter transversely in said valve chamber, whereby said valve member accommodates itself to said valve seat, said valve member having a transverse opening, a transverse rod of a diameter less than the diameter of said opening secured at its opposite ends to the wall of said valve chamber and spaced from the walls of said opening, said transverse rod and opening forming a loose connection permitting said valve member to flow transversely and longitudinally freely in said chamber between the limits of said loose connection, and adjusting means movable towards and away from said valve member and cooperating with said valve member for adjusting the extent of longitudinal movement of the latter away from said valve seat within the limits of said loose connection, and having a convex portion cooperating with the concave portion of the valve member.
